UNITED STATES PATENT OFFICE

HERBERT KATZMAN, OF NEW YORK, N. Y., ASSIGNOR TO WILLIAM WILLHEIM CO., INC.,
OF NEW YORK, N. Y.

DESIGN FOR A TEXTILE FABRIC OR SIMILAR ARTICLE

Application filed September 28, 1932. Serial No. 45,087. Term of patent 3½ years.

To all whom it may concern:

Be it known that I, HERBERT KATZMAN, a citizen of the United States of America, residing at 225 Central Park West, New York, New York, have invented a new, original, and ornamental Design for a Textile Fabric or Similar Article, of which the following is a specification, reference being had to the accompanying drawing, forming a part thereof.

The figure is a plan view of a textile fabric showing the complete width of my new design except for the portion between the break

lines which is similar to that on either side thereof. The dot and dash lines on the drawing outline the design unit, which unit is repeated in regular succession as indicated by the extensions beyond the unit boundaries. The drawing is lined to indicate shading.

I claim:

The ornamental design for a textile fabric or similar article as shown and described.

In testimony whereof I have signed this specification.

HERBERT KATZMAN.
